(57) **CLAIM**

I claim the ornamental design for a furniture unit, as shown and described.

DESCRIPTION

FIG. 1 is a perspective view of a furniture unit;
FIG. 2 is a front elevational view of the furniture unit;
FIG. 3 is a rear elevational view of the furniture unit;
FIG. 4 is a top elevational view of the furniture unit;
FIG. 5 is a bottom elevational view of the furniture unit;
FIG. 6 is a side elevational view of the furniture unit; and,
FIG. 7 is a side elevational view of the furniture unit.
The broken line showing is for illustrative purposes only and
forms no part of the claimed design.
